UNITED STATES PATENT OFFICE.

OLIVER L. DURFLINGER, OF SHELBYVILLE, INDIANA.

FOOT-GUARD FOR RAILWAYS.

SPECIFICATION forming part of Letters Patent No. 501,927, dated July 25, 1893.

Application filed February 8, 1893. Serial No. 461,415. (No model.)

To all whom it may concern:

Be it known that I, OLIVER L. DURFLINGER, a citizen of the United States, residing at Shelbyville, in the county of Shelby and State 5 of Indiana, have invented certain new and useful Improvements in Foot-Guards for Railroad Switches, Crossings, &c., of which the following is a specification.

The object of my said invention is to provide a guard to be used in connection with guard-rails, switches, crossings, frogs, &c., in railroad tracks, which will effectually prevent persons from being caught therein when walking across or among such tracks. Said invention 15 will be first fully described and then pointed out in the claims.

Referring to the accompanying drawings, which are made a part hereof, and on which similar letters of reference indicate similar parts, Figure 1 is a top or plan view of a guard constructed in accordance with my invention, in use in connection with the end of a guard-rail; Fig. 2 a longitudinal vertical section of the same, and Figs. 3 and 4 transverse sectional views thereof on the dotted lines 3 3 25 and 4 4, respectively, in Figs. 1 and 2.

In said drawings the portions marked A represent the rail of a railroad track; B the guard rail; C the main portion of my improved 30 guard; D a bottom plate therefor, and E a spring or springs interposed between said guard and said bottom plate. The track rail A and guard rail B are or may be of the ordinary or any desired form, and are mounted 35 on ties, T, or otherwise, as may be desired, all of these being generally of the ordinary railway construction.

The guard C is formed to fit between the rails A and B at the end where the guard-rail 40 is usually bent away from the track-rail, and normally is intended to be in contact with the heads or upper portions of said rails, and slope down thence gradually to a tie just beyond the end of the guard-rail, where it is secured 45 by spikes, S, or otherwise, which spikes, when used, preferably pass through slots in said guard, and thus secure it strongly in place. The forward end of the guard is bent or curved 50 downwardly somewhat, to overhang the end of the bottom plate, which is curved upwardly,

this formation excluding snow, dirt, and other extraneous matter which might otherwise get under the guard, and thus interfere with its operation.

The bottom plate D is secured to the ties, 55 or otherwise, below the guard C, and its end is bent upward, as has just been described, to close the space between the guard and said bottom plate. It has a perforation through which a bolt or stem C', secured to the guard, 60 extends.

The spring E is placed between the guard C and the bottom plate D, and serves to support the former. It is preferably a coiled spring surrounding the bolt or pin C', which 65 retains it in place, but, of course, other forms of springs may be substituted. A single spring is shown, and this will usually be found sufficient, but the number may of course be increased if desired. The spring or springs 70 are adjusted to support such a weight as would usually come upon the guard when stepped on by a person or animal, but to yield when the flanges of the car wheels come in contact therewith. The guard is thus in the former 75 case to all intents and purposes a rigid structure, preventing the feet of persons or animals from getting between the rails or the sides of a switch or frog at the points where placed; while so far as the rolling stock of the rail-road is concerned, the guard presents no obstruction to or interference with its usual and ordinary operation.

My invention while only illustrated in connection with the guard-rail, is obviously as capable of use in connection with any form of track - rail intersections, such as switches, frogs and crossings, and I desire to be understood as claiming all such modifications, which are of form merely, as will be readily understood.

Having thus fully described my said invention, what I claim as new, and desire to secure by Letters Patent, is—

1. The combination of the guard pivotally 95 secured to the ties at one end by spikes S driven through holes therein suitably formed to permit the pivotal motion, a supporting plate secured to other ties below the free end of said guard, and a spring interposed be- 100

tween said plate and said guard whereby said guard is normally held in raised position, said guard being constructed and operating substantially as set forth.

- 5 2. The combination of a guard C secured at one end, with its free end curved downwardly, a bottom plate D having its corresponding end curved upwardly, and a spring interposed between them, substantially as set forth.
- 10 3. The combination of a guard C secured at one end, the other or free end being formed to fit between the rails or frog or switch sides, as shown, and provided with a bolt or pin C'

extending downwardly, the bottom plate D having a perforation for said pin or bolt, and 15 a spring E interposed between the parts C and D and surrounding the pin or bolt C', substantially as shown and described.

In witness whereof I have hereunto set my hand and seal, at Indianapolis, Indiana, this 20 3d day of February, A. D. 1893.

OLIVER L. DURFLINGER. [L. S.]
